Primary Examiner — Carla J Wright(57) **CLAIM**

The ornamental design for a case for a smartphone, as shown and described.

DESCRIPTION

FIG. 1 is a front isometric view of a case for a smartphone; FIG. 2 is a rear isometric view thereof; FIG. 3 is a front view thereof; FIG. 4 is a rear view thereof; FIG. 5 is a left view thereof; FIG. 6 is a right view thereof; FIG. 7 is a top view thereof; and, FIG. 8 is a bottom view thereof.

The dot-dash broken lines in FIGS. 1, 3, and 8 form no part of the claimed design and represent the bounds of the claimed design. The dash-dash broken lines throughout the drawing figures form no part of the claimed design and depict portions of the case for smartphone that form no part of the claimed design.
